VARIABLE PITCH AIRSCREW

Grettir Algarsson, Montreal, Quebec, Canada, assignor to Algarsson Engineering Company Limited, Montreal, Quebec, Canada

Application August 12, 1938, Serial No. 224,449
In Canada June 28, 1938

16 Claims.

(Cl. 170—163)

This invention relates to variable pitch air-screws and seeks to provide means whereby the R. P. M. of the air-screw may be maintained at any selected value through variation of the pitch setting of the air-screw blades.

According to the invention a balance is established between the twisting moments in the blades, modified by centrifugal means, and torque transmitted through a gear train to or from a governor controlled mechanism. This governor controlled mechanism may consist of pneumatic or hydraulic pumps or motors, or of their electrical equivalent.

The use of the invention enables the operator of an aircraft to use the full power of the engine under all conditions. At will the operator may reverse the thrust of the air-screw thus providing an effective air brake. The air-screw blades can be fully feathered in the event of engine stoppage. Conventional blades may be used but the employment of a special blade form permits the feathering operation to be accomplished automatically.

The gear train through which torque is transmitted consists of two stages, the first of which lies within the air-screw hub and includes a form of a planetary reducing gear. This first stage is static when the air-screw blades are not changing pitch. The second stage, mounted on the front of the engine, is a transmission from the air-screw hub to the mechanism producing the torque reaction, and is constantly driven by the rotation of the air-screw.

In order that the invention may be more readily understood reference is made to the drawings in which Figure 1 is a sectional side elevation of a two bladed air-screw employing a pump-motor and a compressor with the valve mechanism in the neutral position and indicating the engine in the outside elevation.

Figure 2 is a sectional front elevation on the line 2—2 of the air-screw hub shown in Figure 1.

Figure 3 is a partial sectional view of the pump-motor showing the location of the exhaust port, the arrows indicating the flow of the air during the exhaust stroke, the pistons and connecting rods being shown in dotted lines.

Figure 4 is a view similar to Figure 3 but showing the location of the inlet port and the flow of air during the intake stroke.

Figure 5 is a view similar to 3 and 4 but shows both exhaust and intake ports closed, the piston affected being shown dotted at both top and bottom dead centre positions.

Figure 6 is a partial sectional view of the

throttle valves showing one valve closed and the other open.

Figure 7 is a view similar to Figure 6 but showing the valves in the reverse position.

5 Figure 8 is a sectional side elevation of a two bladed air-screw hub mounted on a splined shaft.

Figure 9 is a sectional front elevation on the line 9—9 of Figure 8.

10 Figure 10 is a side elevation of an air-screw having a hub similar to that shown in Figures 1 and 2 but employing a single pump to reduce the pitch in opposition to overbalancing counterweights.

Figure 11 is a side elevation of an air-screw 15 having a hub similar to that shown in Figures 1 and 2 but employing gear pumps in place of the reciprocating type.

Figure 12 is a diagram showing the relation of the various forces acting on a blade in the 20 case of an air-screw employing a pump-motor and a compressor. The pump-motor is shown operating as a compressor.

Figure 13 is a diagram similar to Figure 12 but shows the pump-motor acting as a motor.

25 Figure 14 is a diagram showing the relation of the various forces acting on a blade in the case of an air-screw employing a pump and an overbalancing counterweight.

Figure 15 is a diagram similar to Figure 13 but 30 showing the blade in a negative position and receiving reverse thrust.

Figure 16 is a graph illustrating generally the aerodynamic and centrifugal moments generated in the blades and in the eccentric weights.

35 Figure 17 is a section at the line 17 of Figure 8 showing the eccentric weights only in full lines, the upper weight being in section.

40 The device shown and described in this application is an improvement upon the device shown and described in my co-pending application for Patent Serial No. 174,514, filed November 15, 1937.

Referring to the drawings, the engine shaft 45 15 has a tapered end 16 on which is keyed the flanged sleeve 17. This sleeve 17 is retained on the tapered end of the shaft 15 by means of the keeper nut 18, which in turn is locked by the locking ring 19.

Mounted on the sleeve 17 is the rear half 20 of the hub casing which has a flange 21 bolted to the flange 22 of the sleeve 17. The front half 23 of the hub casing is bolted directly to the rear half 20.

The air-screw blades 24 and 25 are anchored directly to each other through the ball bearings 26. The centrifugal pull of the blade 24 is trans-

mitted to the inner races of the bearings 26 through the axial pin 27 and its head 28. This centrifugal pull is balanced by that of the opposite blade 25 transmitted to the outer races of the bearings 26 through the sleeve 29 and its shoulder 30.

The blades 24 and 25 are located in the hub casing by the bearings 31 which transmit all the bending loads from the blades to the hub casing and are adjusted by the adjustment rings 32 which latter are secured in any desired setting by the locking keys 33.

The adjustment rings 32 provide a means of preloading the bearings 26 and 31 and at the same time permit accurate balancing of the whole airscrew by slackening one adjustment ring and tightening the other, thus displacing both blades and the ball bearings 26 in the same direction along their common axis.

In the above arrangement the common axis of the blades is forward of the end of the engine shaft. Figures 8 and 9 illustrate a variation applicable when it is desired to penetrate the centre of the hub or when three or more blades are to be employed.

The blades 24 and 25 have mounted on their roots within the hub casing bevel gears 34 which mesh with the bevel gear 35 journalled on the front half 23 of the hub casing and the bevel gear 36 journalled on the locking ring 19. This bevel gear 36 is shown in Figures 8 and 9 as journalled on the hub casing.

These bevel gears 35 and 36 ensure equal rotation of the blades in opposite directions, thus rendering impossible unequal pitch setting of the blades.

Each of the bevel gears 34 carries a weight 37 located eccentrically with regard to the axis of the blades within the hub casing.

As the blades turn about their axes towards high pitch the weights 37 turn with them approaching the plane of rotation of the airscrew. The distance between each weight 37 and the airscrew axis, therefore, increases as the pitch of the blades increases and decreases as the pitch of blades decreases. The centrifugal force generated in these weights by the rotation of the airscrew varies directly as the distance from the airscrew axis, R. P. M. being constant and tends always to turn the blades to a higher pitch setting.

Cut in the rear face of the bevel gear 36 is the internal gear 38 from which a gear train leads to a torque producing mechanism. This gear train comprises two stages.

The first stage is composed of the planetary gears 39 and 40, the planetary gear ring 41, the spur gears 42 and 43 and the drive ring 44. The drive ring 44 is journalled on the sleeve 17. The planetary gears mesh with the internal gear 38 and are connected through the shafts 45 with the planetary gears 40 which mesh with the internal gear 46 cut in the rear half 20 of the hub casing. These shafts 45 are journalled in the planetary gear ring 41 in which is cut a gear 47 which meshes with the spur gears 42, and is journalled on the flanged sleeve 17.

The spur gears 42 are connected with the spur gears 43 by the shafts 48 which pass through the flange 22 of the sleeve 17, being journalled in the bosses 49 in the rear half 20 of the hub casing. The spur gears 43 mesh with the gear 50 on the drive ring 44 thus completing the first stage of the gear train.

The planetary gears 39 are of slightly larger

pitch diameter than the planetary gears 40, consequently rotation of these gears with the shafts 45 on which they are mounted results in the gradual rotation of the internal gear 38 in relation to the internal gear 46 cut in the hub casing. Rotation of the internal gear 38 and the bevel gears is attended by proportional rotation of the planetary gear ring 41. This proportion or ratio depends on the pitch diameters of the planetary gears and the internal gears with which they mesh, thus providing a compact and robust gear train, giving the planetary gear ring 41 a mechanical advantage over the bevel gears and through them the blades. Rotation of the planetary gear ring is transmitted to the drive ring 44 through the spurs 42 and 43.

The various gears comprising the first stage of the gear train moves in relation to each other only when the airscrew blades are changing pitch. At all other times, when the airscrew is rotating, they operate in a static condition transmitting from the drive ring 44 whatever torque is necessary to maintain the pitch setting. The second stage of the gear train, which is constantly running, consists of the reducing gears 51 and 52, the idler gear 53 and the gear 54. The gear 51 meshes with the gear 55 cut in the drive ring 44 and is connected with the gear 52 by the shaft 56. The rotation of the gear 52 is transmitted to the gear 54 through the idler gear 53.

The gear 54 is mounted on the crank shaft 57 of a pneumatic pump-motor 58 which, in the form of the invention illustrated in Figure 1, is the mechanism producing torque reaction.

The whole gear train including both stages is permanently connected and can at any moment transmit drive from either end between the airscrew blades and the pump-motor.

The following description of the pump-motor 58 will be more clearly understood if reference is made to Figures 3, 4 and 5.

This pump-motor 58 is of the four cylinder variety and uses its crank case 59 as a discharge manifold. An annular intake manifold 60 leads to an inlet port 61 in each of the cylinders 62. Each piston 63 acts as a slide valve controlling the intake and discharge of an adjacent cylinder. Each cylinder 62 is provided with a duct 64 leading from the cylinder head to the port 55 in the wall of an adjacent cylinder on one side, and on the other side has in its own wall a port 65 leading to the head of the other adjacent cylinder through its duct 64. A recess 66 in each piston 63 connects the inlet port 61 with the port 65 when the piston is below the half stroke position. Figure 4 illustrates diagrammatically this position, the arrows indicating the flow of air from the intake manifold and the direction of movement of the piston affected. Figure 3 illustrates a position in which the piston acting as a slide valve is above the half stroke point. The inlet port 61 is now covered by the piston skirt 67 and the port 65 is open to the crank case 59, thus permitting air to pass from the cylinder affected to the crank case during the exhaust stroke. Figure 5 illustrates the half stroke position of the piston acting as a slide valve and shows both ports 61 and 65 closed. As indicated in this figure, this position occurs at both top and bottom dead centres of the piston affected.

A compressor 68, driven by the engine 69, is identical in construction with the pump-motor 58 but runs at approximately double the speed. A discharge line 70 from the compressor 68 is

connected to the intake 71 of the pump-motor 58, having a branch connection 72 leading from the discharge line 70 to a throttle valve 73. An exhaust line 74 leads from the crank case 59 of the pump-motor 58 to another throttle valve 75.

The throttle valves 73 and 75 form a part of the valve stem 101 in the engine driven governor 76 and are so arranged that when the governor is at mid stroke both throttle valves are wide open. As the governor responds to increased speed the valve stem 101 moves upward against the pressure of the spring 79 closing the throttle valve 75 and leaving the throttle valve 73 wide open. This position of the throttle valves is illustrated diagrammatically in Figure 6. As the governor responds to reduced engine speed the valve stem 101 moves downward under pressure of the spring 79 opening the throttle valve 75 and, reaching the full open position at the mid stroke of the governor. As the governor continues to respond to decreasing engine speed the throttle valve 73 closes, leaving the throttle valve 75 open. This latter position of the valves is illustrated diagrammatically in Figure 7.

The throttle valves 73 and 75 each have four outlet ports numbered 77 and 78 respectively. The diameter of each outlet port is half that of the single inlet line 72 or 74. This arrangement halves the length of stroke of the valves and confines the throttling to the outlet ports.

The setting of the governor 76 is adjusted by varying the setting of the spring 79. This variation is accomplished by manual remote control of the worm 80.

A remotely controlled lever 81 is provided by means of which the pilot can simultaneously close the valve 75 and open the valve 73. When the pilot releases the lever 81 a spring 82 returns it to the position shown in Figure 1 in which it does not interfere with the operation of the governor.

After passing through the throttle valves 73 and 75 the air may be allowed to escape or may be returned through pipe connections, not shown, to the intake of the compressor 68. The exhaust line 74 from the pump-motor 58 is provided with a relief valve 84. A branch line 85 leads from a compressed air reservoir 86 to the exhaust line 74. A valve 87 controls the flow of air from the reservoir 86 to the branch line 85 which is provided with a pressure gauge 88 within the view of the pilot.

Operation of the propelling unit of Figure 1

In the operation of this invention, the twisting moments generated in the eccentric weights 37 nearly balance the resultant of the aerodynamic and centrifugal twisting moments produced by the blades themselves. Owing to the arrangement of the blade mountings, the friction opposing change of pitch is reduced to a minimum, so that the load on the gear train under normal running conditions is reduced to a low value, being only that amount required to correct the balance of twisting moments plus the minimized friction.

Pitch control of the airscrew blades is effected through the gear train in the following manner:

The governor is adjusted by the operator to any desired value of R. P. M. by means of the remotely controlled worm 80. If the R. P. M. rise above this desired value the governor 76 moves the valve stem 101 carrying the valves 73 and 75 upward closing the ports 78 and leaving the ports 77 wide open. The discharge of the pump

motor is thus restricted and pressure built up in the exhaust line 74 and the crank case 59. The pump motor 58 is now under load as a compressor and a torque reaction or drag is applied through the constantly running second stage of the gear train to the drive ring 44. The drag on the drive ring 44 is transmitted through the first stage of the gear train and the bevel gears to the airscrew blades, turning them to a higher pitch setting, increasing the load upon the engine and thus arresting increase in R. P. M. The gear ratio provided by the planetary gearing, located in the first stage of the gear train operates to convert a small drag upon the drive ring into a comparatively large twisting moment tending to change the pitch of the blades; it also serves to minimize sudden or uneven pitch changing movements.

If the R. P. M. fall below the desired value the spring 79 moves the valve stem 101 downwards closing the ports 77 and leaving the ports 78 wide open. The discharge of the pump motor 58 is now unrestricted and the discharge of the compressor 68 is applied to the intake of the pump

motor. The compressor 68 runs faster than the pump motor 58 and consequently the air discharged by it is forced under pressure through the intake of the pump motor thus causing the latter to act as an air motor, overrun the gear train, turn the blades to a lower pitch setting, relieve the load upon the engine and thus arrest decrease in R. P. M.

In other words by loading the pump-motor 58 as a compressor, a torque reaction is transmitted to the blades dragging them into a higher pitch setting, lower pitch settings being achieved by loading the pump-motor 58 as an air motor, thus causing it to overrun the gear train and apply torque to the blades in the opposite sense.

The arrangement of the pump-motor shown, in which the intake and exhaust ports open and close on dead centres of the pistons affected, is advantageous as any leg or lead which might suit the operation of the pump-motor as an air motor would interfere with its operation as a compressor or vice-versa.

The governor will continue to correct the engine R. P. M. to the desired value through alteration of pitch, and consequently of load upon the engine, regardless of the cause of variation.

The graph in Figure 16 shows approximately the relative magnitude of the twisting moments acting upon a blade in a typical case. The loads on the gear train appear in this graph as the vertical distances between two curves. The curve A shows the aerodynamic twisting moments occurring at various pitch settings with power output, R. P. M. and air density constant. The curve I indicates the magnitude of "inherent torque" due to the action of centrifugal force on the blade at various pitch settings, with R. P. M. constant. The curve A+I is the sum of the two curves already described, and the curve C shows the centrifugal twisting moments imparted by the eccentric weight 37.

As the curve A+I represents twisting moments tending to reduce the pitch and the curve C represents twisting moments tending to increase pitch, the vertical distances between the two indicate the twisting moments to be supplied by the torque producing mechanism in order to correct the balance. When changing pitch a small additional load would be placed upon the torque

producing mechanism in order to overcome friction.

Of the three types of twisting moments indicated, I and C are the greatest and, being centrifugal in nature, will vary as the square of the R. P. M. The values indicated by curve A are affected by other variants but are smaller. The loads on the gear train, therefore, should not greatly exceed the proportions indicated.

The diagram in Figure 12 shows the relation of the various forces acting on a blade, when the valve 75 is closed, the valve 73 open and the pump-motor 58 acting as a compressor. The line C indicates the direction of the centrifugal twisting moment exerted by the eccentric weight 31, I indicates the direction of the "inherent torque" due to the action of centrifugal force on the blade, C. P. indicates the position of the centre of pressure, which in this case is shown on the trailing edge side of the axis of rotation of the blade thus applying a twisting moment in the direction of the line marked "thrust," and A indicates the position of the axis of rotation of the blade. The arrows on the pump-motor 58 indicate its direction of rotation and F indicates the direction of the torque reaction transmitted to the blades through the gear train.

Figure 13 is similar to Figure 12 but illustrates the condition when the valve 75 is open, the valve 73 closed and the pump-motor 58 operating as a motor, F indicates the direction of the drive of the pump-motor 58, acting as a motor, transmitted to the blades through the gear train.

In the form of the invention illustrated in Figure 10, in which a single pump is employed in conjunction with overbalancing counterweights, the discharge line 74 is connected to the valve 73, and the compressor 68 and valve 75 are eliminated. The governor 76 operates the valve 73 in the manner already described but causes the pump-motor 58, acting as a compressor, to drag the airscrew blades towards low pitch against the action of the eccentric weights 31, which latter are in this case sufficiently powerful to turn the blades into the feathered position when the valve 73 is fully open.

The diagram in Figure 14 refers to an example in which a single pump is used in conjunction with an overbalancing counterweight as illustrated in Figure 10. The letters used to indicate the various forces correspond with those used in Figures 11 and 12.

The diagram in Figure 15 shows the relation of the forces acting upon a blade when an airscrew similar to that indicated in Figure 14 is used as an air brake.

A feature of the invention using the above described mechanism is that the pilot can at any time move the blades into their extreme low pitch setting and use the engine as a brake. This is accomplished by closing the throttle and then opening it again, the sequence of operations being as follows:

The pilot closes the throttle, thereby reducing the R. P. M. of the engine. The governor automatically closes the valve 73 thus causing the pump-motor 58 to act as a motor thereby turning the blades to a lower pitch setting and permitting the engine to regain the desired value of R. P. M., to which the governor is adjusted. As the pilot continues to close the throttle the same process will continue, the pitch being reduced until the load on the engine reaches a minimum when the blades have reached a pitch setting at which no thrust is developed. At this stage the

engine is so far throttled down that it can only maintain the desired value of R. P. M. with the load at a minimum. The pilot closes the throttle still further and the R. P. M. of the engine will fall below the desired value regardless of the pitch setting of the blades. The governor however will continue to close the valve 73 as long as the R. P. M. are below the desired value forcing the blades into a lower pitch setting and causing the thrust to reverse. This will increase the load on the engine slowing it down and causing the governor to close the valve 73 even further. This sequence of reduced pitch attended by increased load and reduced R. P. M. is cumulative and results in the blades being turned to their extreme low pitch setting. The blades are prevented from going to any lower pitch setting by suitable stops on the inside of the hub casing but not shown. If the pilot now reopens the throttle, the engine will be under a heavy load, producing reverse thrust, and will be unable to regain the desired value of R. P. M. to which the governor is adjusted. The governor will continue to keep the valve 73 closed and the blades will remain in their extreme low pitch setting regardless of manipulations of the throttle. In other words the pilot can use the engine as a brake to any extent within its power without fear of forcing the blades into the forward thrust range or of racing the engine.

When it is desired to restore the airscrew to its normal condition of forward thrust, the pilot closes the throttle, operates the lever 81 and then reopens the throttle. The mechanical operation is as follows: When the pilot closes the throttle, the R. P. M. of the engine fall off regardless of the pitch setting of the blades. When he operates the lever 81 he opens the valve 73 and closes the valve 75, causing the pump-motor 58, acting as a compressor, to turn the blades to their extreme high pitch setting. This extreme high pitch setting is the "feathered" or "infinite pitch" position.

When the pilot reopens the throttle, the R. P. M. of the engine will increase and when he releases the lever 81 the governor will again close the valve 73 causing the pitch of the blades to decrease until a pitch setting giving normal forward thrust is reached.

A further feature of the invention is that in the event of engine stoppage from any cause the pilot can cause the blades to turn to the "feathered" position, thus reducing drag and losses due to turbulence of the air flowing over adjacent portions of the wings. This can be accomplished, if the engine has not ceased to revolve, by operating the lever 81 in the manner just described and keeping it in operation until after the engine has stopped. If the engine has already ceased to rotate, the blades can still be moved into the "feathered" position by operating the lever 81 and then opening the valve 80 and permitting compressed air to flow from the reservoir 86 to the exhaust line 74 and the crank case of the pump-motor 58, thus causing the latter to act as an air motor in a direction opposite to its normal rotation and turn the blades into the "feathered" position. In this case the air exhausted from the pump-motor 58, operating as a motor in reverse, escapes through the valve 73 which is opened by the same operation of the lever 81 which closes the valve 75.

This invention has been described as applied to blades similar to those in common use, but lends itself very readily to the use of blades of

special plan form in which the centres of pressure along the blades are on the trailing edge side of the axis of rotation. When using blades of the last mentioned variety there is no necessity for the use of the reservoir 86, as the blades will automatically "feather" on the principle of the weather vane, and the lever 81 will be necessary only when it is desired to resume forward thrust after using the engine as a brake. This feathering type of blade has a tendency to respond automatically to variations in airspeed, altitude, etc. imposing less load on the pitch controlling mechanism.

In the form of the hub illustrated in Figures 8 and 9 the engine shaft 15 has a splined end 89 on which both halves 20 and 23 of the hub casing are mounted by means of cones 90. The blades 24 and 25 are located in the hub casing in the same manner as illustrated in Figures 1 and 2 but, in place of the common central bearing 26, bearings 91 transfer the centrifugal pull of each blade to an anchoring barrel 92 which encloses the splined shaft but does not bear upon it or the hub casing. This structure can be further modified to accommodate three or more blades. In both forms of blade mountings shown, the blades and their centrifugal bearings and attachments are assembled separately and inserted as a unit in place against the rear half of the hub casing.

In the foregoing description, air pumps or a combination of air pumps and air motors have been described as the sources of the torque reaction. It will be understood that these pumps and motors could be adapted to employ any gaseous mixture, or could be hydraulic employing oil or other fluids as an operating medium. They could also be replaced by generators and motors employing electricity, without altering the general arrangement or efficiency of control. In the latter case, rheostats or some other load varying device would be substituted for the valves referred to.

Operation of the form of Figure 11

The principle of operation in this form of the invention is identical with that of the form illustrated in Figure 1, the differences are purely mechanical and consist in the substitution of gear pumps for the reciprocating variety, the addition of relief valves protecting the system from excessive pressures and the provision of return lines closing the system.

A gear pump 93 occupies the same position and performs the same function as the pump motor 58 illustrated in Figure 1, and a gear pump 94 similarly takes the place of the compressor 68. The pipe lines 10, 12 and 14 are arranged in the same way as illustrated in Figure 1 and fulfill identical functions. The relief valve 95 is fitted between the lines 10 and 14 protecting the former against excessive pressure by providing a bypass. In the same way a relief valve 96 protects the line 14. A return line 97 connects the discharge of the relief valve 96 with the intake 98 of the pump 94. Further return lines 99 and 100 connect the discharges of the valves 73 and 75 with the return line 91 thus closing the pump system.

The purpose of Figure 11 is to illustrate the use of an alternative type of pump and to show the application of relief valves and return lines which were omitted from Figure 1 for the sake of clarity, being protective devices only and not essential to the operation of the invention.

From the foregoing, it will be apparent that this invention provides a variable pitch airscrew which may be set to run at any value of R. P. M. selected by the pilot, in which the blades may be feathered in the event of engine stoppage, which may be made to develop reverse thrust at the will of the pilot and employed either as a brake or as an aid to maneuvering on the ground, or, in marine aircraft, the water: which is positive in action, using as it does direct mechanical connection between the rotating airscrew and the statically mounted control means and confining to the latter the selected media of operation whether pneumatic, hydraulic or electric.

15 What I claim is:

1. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, a statically mounted torque producing mechanism connected with the other end of said gear train for pitch changing movement of the blades, said gear train containing a reducing gear carried by the hub and giving the torque producing mechanism a mechanical advantage over the airscrew blades, and means to control said mechanism to vary the torque produced both in magnitude and direction to effect increase or decrease of pitch setting of the airscrew blades.

2. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, a statically mounted torque producing mechanism connected with the other end of said gear train for pitch changing movement of the blades, said gear train containing a reducing gear carried by the hub and giving the torque producing mechanism a mechanical advantage over the airscrew blades, means to control said mechanism to vary the torque produced both in magnitude and direction to effect increase or decrease of pitch setting of the airscrew blades, and a governor controlling said means in agreement with variations in rotational speed of the airscrew from a selectable datum.

3. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, and a governor controlling said means in agreement with variations in rotational speed of the airscrew from a selectable datum.

4. In a variable pitch airscrew of the kind in which the blades of the airscrew are connected together to effect equality of pitch setting, a

counterweight nearly balancing the aerodynamic and other forces acting on each blade, a gear train capable of transmitting rotation from either end and connected at one end with the airscrew blades, a hydraulic statically mounted pump, which may be operated as a motor, connected with the other end of said gear train for pitch changing movement of the blades, a second hydraulic statically mounted pump having its discharge connected to the intake of the first hydraulic pump, means to control the intake or discharge of said first pump to vary the magnitude or reverse the direction of the torque applied by said pump to the gear train to effect increase or decrease of pitch setting of the air screw blades, and a governor controlling said means in agreement with variations in rotational speed of the airscrew from a selectable datum.

5. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, said gear train comprising two stages, the first of which is carried by the airscrew and gives the second stage a mechanical advantage over the blades, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, and a governor controlling said means in agreement with variations in rotational speed of the airscrew from a selectable datum.

6. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, said gear train comprising two stages, the first of which is carried by the airscrew and gives the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the air screw blades and a governor controlling said means in agreement with variations in rotational speed of the airscrew from a selectable datum.

7. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, said gear train comprising two stages, the first stage, carried by the airscrew, containing

5 a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, and a governor controlling said means in agreement with variations in rotational speed of the airscrew from a selectable datum.

8. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, said gear train comprising two stages, the first stage, carried by the airscrew, containing a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, a manual control to the intake or discharge of said pump to cause said pump to apply a torque through the gear train to the airscrew blades turning them to their extreme high pitch or feathered position, and a governor controlling said means in agreement with variations in rotational speed of the airscrew from a selectable datum.

9. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, said gear train comprising two stages, the first stage, carried by the airscrew, containing a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, a relief valve on the discharge side of said air pump, means to control the intake or discharge of said pump to vary the magnitude or reverse the direction of the torque applied by said pump to the gear train to effect increase or decrease of pitch setting of the airscrew blades, a manual control to the intake or discharge of said pump to cause said

pump to apply a torque through the gear train to the airscrew blades turning them to their extreme high pitch or feathered position, and a governor controlling said means in agreement with variations in rotational speed of the airscrew from a selectable datum.

10. In a variable pitch airscrew of the kind in which the blades of the airscrew are connected together to effect equality of pitch setting, a counterweight nearly balancing the aerodynamic and other forces acting on each blade, a gear train capable of transmitting rotation from either end and connected at one end with the airscrew blades, said gear train comprising two stages, the first stage, carried by the airscrew, containing a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, a relief valve on the discharge side of said air pump, means to control the intake or discharge of said pump to vary the magnitude or reverse the direction of the torque applied by said pump to the gear train to effect increase or decrease of pitch setting of the airscrew blades, a charged reservoir connected to the discharge of the air pump adapted to be used therewith to turn the blades to their extreme high pitch or feathered position, a manual control to the intake or discharge of said pump to cause said pump to apply a torque through the gear train to the airscrew blades turning them to their extreme high pitch or feathered position, and a governor controlling said means in agreement with variations in rotational speed of the airscrew from a selectable datum.

11. In a variable pitch airscrew having two blades rotatably mounted on a hub casing and connected together to effect equality of pitch setting, a common central bearing taking the centrifugal pull of both blades, a counterweight nearly balancing the aerodynamic and other forces acting on each blade, a gear train capable of transmitting rotation from either end and connected at one end with the airscrew blades, said gear train comprising two stages, the first stage, carried by the airscrew, containing a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, a manual control to the intake or discharge of said pump to cause said pump to apply a torque through the gear train to the airscrew blades turning them to their extreme high pitch or feathered position, and a governor controlling said means in agreement with variations in rotational speed of the airscrew from a selectable datum.

12. In a variable pitch airscrew having two blades rotatably mounted on a hub casing and connected together to effect equality of pitch setting, a sleeve extending from one blade forming a housing, a rod extending from the other blade forming a shaft mounting, a common central bearing carried by said housing and shaft mounting and taking the centrifugal pull of both blades, a gear train capable of transmitting rotation from either end and connected at one end with the airscrew blades, a statically mounted torque producing mechanism connected with the other end of said gear train for pitch changing movement of the blades, said mechanism comprising a plurality of fluid pressure means connected together and adapted to be operated either as a pump or as a fluid motor and means to control said mechanism to vary the torque produced both in magnitude and direction to effect increase or decrease of pitch setting of the airscrew blades.

13. In a variable pitch airscrew having two or more blades rotatably mounted on a hub casing and connected together to effect equality of pitch setting, a central anchoring barrel taking the centrifugal pull of all the blades, a bearing taking the centrifugal pull of each blade carried by the anchoring barrel, a counterweight nearly balancing the aerodynamic and other forces acting on each blade, a gear train capable of transmitting rotation from either end and connected at one end with the airscrew blades, said gear train comprising two stages, the first stage, carried by the airscrew, containing a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, a manual control to the intake or discharge of said pump to cause said pump to apply a torque through the gear train to the airscrew blades turning them to their extreme high pitch or feathered position, and a governor controlling said means in agreement with variations in rotational speed of the airscrew from a selectable datum.

14. In a variable pitch airscrew having two or more blades rotatably mounted on a hub casing and connected together to effect equality of pitch setting, a central anchoring barrel taking the centrifugal pull of all the blades, a bearing taking the centrifugal pull of each blade carried by the anchoring barrel, a gear train capable of transmitting rotation from either end and connected at one end with the airscrew blades, a statically mounted torque producing mechanism connected with the other end of said gear train for pitch changing movement of the blades, said mechanism comprising a plurality of fluid pressure means connected together by a system of conduits, each of the fluid-pressure means being adapted to be operated, with outlet to the other of said means, as a pump or as a fluid motor and means to control said mechanism to vary the torque produced both in magnitude and direc-

tion to effect increase or decrease of pitch setting of the airscrew blades.

15. In a variable pitch airscrew having two or more blades rotatably mounted on a hub casing and connected together to effect equality of pitch setting, a central anchoring barrel taking the centrifugal pull of all the blades, a bearing taking the centrifugal pull of each blade carried by the anchoring barrel, adjustable bearings mounted on the blades locating said anchoring barrel, a counterweight approximately balancing the aerodynamic and other forces acting on each blade, a gear train capable of transmitting rotation from either end and connected at one end with the airscrew blades, said gear train comprising two stages, the first stage, carried by the airscrew, containing a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, a manual control to the intake or discharge of said pump to cause said pump to apply a torque through the gear train to the airscrew blades turning them to their extreme high pitch or feathered position, and a governor controlling said means in agreement with variations in rotational speed of the airscrew from a selectable datum.

16. In a variable pitch airscrew having two or

more blades rotatably mounted on a hub casing and connected together to effect equality of pitch setting, a central anchoring barrel having a central bore concentric with the axis of the airscrew and adapted to take the centrifugal pull of all the blades, a bearing taking the centrifugal pull of each blade carried by the anchoring barrel, adjustable bearings mounted on the blades locating said anchoring barrel, a counterweight approximately balancing the aerodynamic and other forces acting on each blade, a gear train capable of transmitting rotation from either end and connected at one end with the airscrew blades, said gear train comprising two stages, the first stage carried by the airscrew, containing a planetary gear system located concentrically in relation to the airscrew axis and giving the second stage a mechanical advantage over the blades, a drive ring rotatable about the airscrew axis connecting the two stages of the gear train, a statically mounted air pump, which may be operated as a motor, connected with the other end of said gear train for pitch changing movement of the blades, a compressor adapted to deliver air to the intake of said air pump, means to control the intake or discharge of said pump to vary the magnitude or reverse the direction of the torque applied by said pump to the gear train to effect increase or decrease of pitch setting of the airscrew blades, a manual control to the intake or discharge of said pump to cause said pump to apply a torque through the gear train to the airscrew blades turning them to their extreme high pitch or feathered position, and a governor controlling said means in agreement with variations in rotational speed of the airscrew from a selectable datum.

GRETTIR ALGARSSON.
